CLAIM

The ornamental design for a shower head, as shown and described.

DESCRIPTION

FIG. 1 is a front elevational view of a shower head showing my new design;

FIG. 2 is a side elevational view thereof; and,

FIG. 3 is rear elevational view thereof.

The top view, bottom view, and side elevational view not shown are identical to the side elevational view shown.

FIG. 3
